FLOW CONTROLLED GAS WATER HEATER

Filed May 20, 1929

FIG. I.

FIG. II.

INVENTOR:

ROBERT J. DOUGHERTY,

by Arthur E. Raigz,
Attorney.

UNITED STATES PATENT OFFICE

ROBERT J. DOUGHERTY, OF AMBLER, PENNSYLVANIA, ASSIGNOR TO JOHN WOOD MANUFACTURING COMPANY, OF CONSHOHOCKEN, PENNSYLVANIA, A CORPORATION OF PENNSYLVANIA

FLOW CONTROLLED GAS WATER HEATER

Original application filed June 18, 1928, Serial No. 286,087. Divided and this application filed May 20, 1929. Serial No. 364,600.

This is a division of my application Serial No. 286,087 filed June 18, 1928, for Letters Patent of the United States, which includes claims for automatically operative valves of 5 the differential pressure controlled type hereinafter described.

My invention is particularly applicable to gas-fired water heaters such as described in application Serial No. 171,237 filed February 10 26, 1927, by Victor Mauck for Letters Patent of the United States, and particularly a house heating system including such a heater with thermostatically controlled valves such as described in Victor Mauck's application 15 Serial No. 187,590 filed April 29, 1927, for Letters Patent of the United States.

Such heaters include cellular units comprising congeries of primarily cylindrical thin copper tubes, the ends of which are expanded and soldered together, so that the tubes afford passageways for products of combustion to heat water contained in the space around said tubes. In such heating systems, it is necessary to forcibly circulate 25 the water to prevent accidental overheating of the soldered portions of such units and consequent disintegration thereof, and it is preferable to effect such circulation by an electrically operated pump. However, such 30 pumps are of course, liable to be rendered temporarily inoperative by abnormal condition of their supply circuit, for instance, by the blowing of a fuse. Unless means are provided to practically instantaneously shut off 35 the supply of gas to the burner of such a water heater upon cessation of operation of the means for circulating the water, serious damage to the heater may result, for, at its maximum consumption of gas, such a burner 40 is capable of melting the solder from the joints in the portion of such a heater unit adjacent the burner in approximately ten seconds after cessation of operation of the pump.

45 I have not been able to find upon the market any thermostatically controlled means for shutting off the gas supply to such a burner within the time thus limited. Therefore, the general purpose and effect of this 50 invention is to provide means which are prac-

tically instantaneously operative to shut off or shut down to a minimum, the supply of gas to a burner as the consequence of cessation of operation of a pump embodied in such a heating system as above contemplated. However, it is obvious that my invention is of 55 more general application, and, therefore, I do not desire to limit myself to the specific embodiment thereof herein described.

As hereinafter described, my improved 60 valve includes a disk in cooperative relation with an annular seat and held between two metallic bellows which are subjected to internal pressure from respectively opposite sides of the pump; said valve being held off 65 its seat to permit the flow of gas thru the latter when the pump is not operating but being closed upon its seat to shut off the supply of gas, when the pump is operating.

My invention includes the various novel 70 features of construction and arrangement hereinafter more definitely specified.

In said drawings: Fig. I is a longitudinal sectional view of an automatically operative valve embodying my invention. 75

Fig. II is a diagram showing the essential elements of a gas-fired water heating system embodying elements with which said valve is adapted to cooperate to control the supply of 80 gas to the heater burner.

Referring to Fig. I; the cylindrical tubular casing 1 has gas ports 2 and 3 extending thru its side wall at respectively opposite ends thereof, and the annular valve seat 5 intermediate of said ports, in cooperative relation with the valve disk 6 which is normally held off its seat by the corrugated cylindrical tubular bellows 7 and 8, which extend upon respectively opposite sides thereof in coaxial relation therewith. The outer ends of said 85 bellows 7 and 8 are respectively rigidly connected with plugs 9 and 10 which have screw threads 11 and 12 respectively engaging the opposite ends of said casing 1. The inner ends of said bellows 7 and 8 are respectively 90 rigidly connected with disk heads 14 and 15. Said head 15 has the screw threaded socket 17 for axially adjustable and detachable engagement with the stem 18 of said valve disk 6 so that the latter is rigidly connected with 95 100

said bellows head 15. Said valve 6 has the axially opposite stem 19 fitted in the seat 20 in the bellows head 14; so that said valve disk 6 is resiliently supported in coaxial relation with its annular seat 5 but is axially adjusted so that it is normally held off said seat, as shown.

As hereinafter described, said bellows 7 is supplied with water from the intake conduit 22 of the pump 23, shown in Fig. II, whereas, said bellows 8 is supplied with water from the discharge conduit 24 of said pump; so that when said pump is operating, it subjects the water in said bellows 8 to pressure, whereupon, the internal pressure in the bellows 8 exceeds that in the bellows 7 and the bypass valve disk 6 is closed upon its seat to thus shut off communication between the gas ports 2 and 3 at opposite ends of said casing, to then, and then only, permit gas to be supplied to the heater burner.

Referring to Fig. II, 26 indicates the main gas burner of the heater above contemplated, which is supplied with gas thru the conduit 27, and the function of said valve 6 in the embodiment shown in Fig. II is to instantly stop the supply of gas thru said conduit 27 when said pump 23 is for any reason stopped.

The conduit 28 leads from a municipal gas main or other source of fuel gas under pressure and is connected with the casing 29 below the seat 30 for the main diaphragm valve 31, which is carried by the flexible diaphragm 32 so that it normally gravitates to closed position, to prevent the flow of gas thru said conduit 27 to said burner 26; when the pressure of the gas supply is admitted to opposite sides of said diaphragm through bypass means controlled by said valve 6, as herein-after described.

However, said gas conduit 28 is continually in communication with the gas conduits 33 and 34, which are connected with said diaphragm valve casing 29. Said conduit 34 leads directly to the pilot burner 35 which is normally lit. Said conduit 33 leads directly to the port 2 in the automatic valve casing 1 aforesaid; so that the space at the right hand side of the valve disk 6 in Fig. I is continually directly connected with the gas supply conduit 28. The port 3 of said valve casing 1 is connected with said main diaphragm valve casing 29, above the diaphragm 31 in the latter, by the bypass conduits 33, 36 and 37; so that, when said valve 6 is open, which is its normal, idle, condition; said diaphragm valve 31 is subjected, upon both sides, to the normal pressure of the gas supplied thru the conduit 28, and is then held closed not only by gravity, but by reason of the greater area of said diaphragm 32 exposed to said gas pressure above than below said seat 30.

Said gas conduit 37 is in communication with the switch diaphragm casing 39 below 65 the flexible diaphragm 40 therein, so as to

normally uplift said diaphragm and stop the operation of said pump 23 when the valve 6 is open. Said diaphragm 40 is operatively connected with the electric switch lever 41 which is in cooperative relation with the switch terminals 42 and 43 so that, when said diaphragm 40 lowers, said terminals 42 and 43 are permitted to come in contact and close the circuit between the conductors 45 and 46 to then energize the electric motor 47 which operates the pump 23.

In order to automatically initiate the operation of said main burner 26 and water pump 23; I provide the gas bleed pipe 48 thru which the gas from the conduit 37 may escape into the conduit 34 leading to the pilot burner 35, under control of three thermostatically operative valves, to wit, first, the valve 50 which has the thermostatic tube 51 extending in the hot water fitting 52 of the heater system; which valve is set to close at, say, 200° F. Second, the valve 54 having the thermostatic element 55, is adapted to close at some room temperature, say 70° F., and, third, the safety valve 57 having the thermostatic element 58 and adapted to close when the temperature local to the burner 26 falls below a predetermined degree. However, said thermostatic element 58 is adapted to maintain said valve 57 open whenever the pilot burner 35 is lighted so as to maintain the flame 59.

In order to insure sufficient gas pressure in said conduit 37 to uplift the switch diaphragm 40 when the valve 6 is closed; I provide said main diaphragm valve 31 with a bleed port 60 thru which sufficient gas is supplied to the conduit 37 to uphold said switch diaphragm 40 under normal idle conditions. I also prefer to include in said conduit 37 a fitting 61 constricting the effective area of said conduit to such a degree as to permit the flow therethru of the volume of gas admitted thru the bleed port 60, but offering sufficient resistance to the large volume of gas from the conduit 36 to insure instantaneous closure of the diaphragm valve 31 whenever said differential valve 6 is opened.

The normal cycle of operation is as follows: If the temperature of the room in which said valve 54 is mounted falls below the temperature for which that valve is set; said valve 54 opens and, providing that the pilot burner 35 is lighted so that the valve 57 is held open, and that the temperature of the water in the system and in the container 52 is not above the critical temperature so that said valve 50 is open; the gas pressure below the switch diaphragm 40 is relieved by the escape of gas thru the bleed pipe 48 and said diaphragm falls and effects the closure of the circuit 45, 46 of the electric motor 47 and thus starts operation of the pump 23 to begin the circulation of water in the system. As soon as such circulation is

established, the difference in pressure of the water in the bellows 7 and 8 closes said valve 6, and gas flow thru said valve to the space in the casing 29 above the diaphragm valve 31 being thus stopped; said valve 31 is lifted by the normal gas pressure below it and gas is thus admitted to the main burner 26 thru the valve seat 30 in the main diaphragm valve casing 29. The gas thus supplied to the burner 26 is, of course, ignited by the flame 59 of the pilot burner 35, and the heater 63 continues to operate until either of the automatic control valves 50 or 54 is closed, respectively by rise of temperature of the water 10 in the container 52 above the critical temperature, or rise of temperature of the atmosphere in the room local to the valve 54. Closure of either of said valves 50 and 54 stops the escape of gas from the bleed pipe 20 48, and the gas admitted thru the bleed port 60 uplifts said switch diaphragm 40, breaking the circuit of the motor 47 and stopping the operation of the pump. The instant the pump stops, said valve 6 (which has been held closed by the pressure of water incident to the operation of the pump,) opens, thus admitting the full gas pressure above the main diaphragm valve 31 closing the latter and thus instantaneously stopping the supply 30 of gas to the main burner 26 and thus preventing any danger of overheating and disintegrating the water containers 63 above the same.

I do not desire to limit myself to the precise details of construction, arrangement, or method of operation herein set forth, as it is obvious that various modifications may be made therein without departing from the essential features of my invention, as defined 40 in the appended claims.

I claim:

1. In a gas water heater, the combination with a main gas burner; of a gas supply conduit leading to said burner; a diaphragm 45 valve controlling the flow of gas in said conduit; bypass conduit means adapted to connect opposite sides of said diaphragm valve and thereby cause the latter to close by pressure of the gas supply; a valve controlling 50 said bypass; a water container in cooperative relation with said burner; means arranged to forcibly circulate water through said container, including a pump; means operatively connecting said pump with said bypass valve; 55 whereby, when said pump is operating, said bypass valve is closed and allows said diaphragm valve to be opened by the pressure of the gas supply, and, when said pump stops, said bypass valve is opened and allows said 60 diaphragm valve to be closed by admission of gas pressure to both sides of said diaphragm, and thus reduce the supply of gas to the burner.

2. Apparatus as in claim 1 wherein the 65 diaphragm valve has a gas bleed opening,

bleed pipe in connection with said bleed opening, and a valve controlling said bleed pipe; an electric motor in operative relation with said pump; an electric switch in the motor circuit; and a switch diaphragm operatively 70 connected with said switch and in communication with said bleed opening and bleed pipe; whereby, when said bleed pipe valve is shut, said diaphragm valve is caused to shut by the equalization of gas pressure upon both 75 sides thereof through said bleed opening, and said switch opened and pump stopped.

In testimony whereof, I have hereunto signed my name at Conshohocken, Pennsylvania, this fifteenth day of May, 1929.

ROBERT J. DOUGHERTY.
